UNITED STATES PATENT OFFICE.

ARTHUR C. HOPKINS, OF MINNEAPOLIS, MINNESOTA, ASSIGNOR TO MID-WEST MANUFACTURING COMPANY, OF SIOUX FALLS, SOUTH DAKOTA, A CORPORATION.

VEHICLE ROLLER-JACK.

1,280,475.

Specification of Letters Patent. Patented Oct. 1, 1918.

Application filed April 29, 1918. Serial No. 231,442.

To all whom it may concern:

Be it known that I, ARTHUR C. HOPKINS, a citizen of the United States, residing at Minneapolis, in the county of Hennepin and State of Minnesota, have invented certain new and useful Improvements in Vehicle Roller-Jacks, of which the following is a specification.

This invention relates to an improvement in vehicle roller jacks, and has for one of its objects to provide such a construction that stresses directed to the operating parts will be adequately sustained when lifting comparatively heavy loads. Another object is to provide such a mounting for the standard or lifting-post that it will be limited to a vertical movement. The invention also includes a flexible strand or cable as a substitute for levers, so that excessive weight of parts may be avoided and economy in manufacture may be attained, and such an arrangement for the cable and frame that they will lie closely adjacent to the floor to be unobtrusive.

With the foregoing objects in view and others to be mentioned hereinafter the invention presents a novel construction, combination and arrangement of parts as described herein and claimed, and as illustrated in the accompanying drawing, wherein,

Figure 1 is a broken away side view of the vehicle roller jack, one of the wheels being removed and the axle being in section. Fig. 2 is a broken away view of roller jack in longitudinal section. Fig. 3 is a plan view of the vehicle roller jack. Fig. 4 is a transverse section on line 4-4 of Fig. 3, the swivel being omitted. Fig. 5 is a sectional view showing the mounting of a pulley on a caster-rail. Fig. 6 is a detail showing the preferred pivotal mounting of the hand-lever on the frame and the mounting of the rack bar upon the hand lever.

Referring to the drawing numeral 7 indicates an axle, upon its ends being journaled the pair of wheels 8. I provide a casting 9 having parts *a* and *b* which project, respectively, above and below the axle, the part *a* being provided with a pair of opposed, rearwardly projecting arms 10 for a mounting of a shaft 11 for journaled bearings of a pulley 12. At 13 is indicated a pair of opposed, rearwardly projecting arms pro-

vided for the lower part of the casting 55 which carry a shaft 14 for a mounting of the pulley 15, the arms 13 being somewhat longer than arms 10, so that the pulley 15 may be disposed in a plane outwardly or rearwardly of the pulley 12. 60

The casting 9 is made rigid with the axle by means of suitable keys *c* (Fig. 2) and it is provided with a rectilinear channel 16 opening on its upper end. Seated in the channel is a standard or post 17 substantially of L-shape, its upper end being provided with a swivel 18 for engaging a load to be elevated, the lower end of the casting being provided with a base-plate 19 (Fig. 2) to limit a downward sliding movement 70 of the standard, an outward swinging movement of the standard being prevented by a detent-plate 20 which is provided for the casting.

Means are provided to maintain the channel and the standard in a vertical position at all times, so that a load may be elevated without undue vibration, this being accomplished, in part by a rearwardly projecting frame 21 consisting of a pair of side bars, 80 best shown in Fig. 3, each preferably being rectilinear with upwardly projecting inner end-portions *d* for a rigid mounting on the axle, preferably by means of keys *e* as shown in Fig. 1. 85

On account of the keyed connection as described, the parts may be conveniently manufactured and assembled. The frame, near its rear end, is supported upon casters 22, and is disposed normally in a horizontal 90 position, and on account of the construction as described, the channel 16 and the post are maintained at right angles to the frame.

Numerical 23 indicates a transverse bar or rail which is suitably secured to the rearwardly convergent side-bars of the frame 21. It has end-portions which project outwardly of the frame 21 to provide a mounting for the casters, and it provides a support, as best shown in Figs. 2 and 5, for a 100 mounting of a third pulley 24.

Numerical 25 indicates a hand-lever the pivotal mounting for its lower end being provided by the wrist-pin 26 which connects the rear end of the side-bars of the frame 21, said lever being provided near its lower end with a curved rack bar 27.

Numerical 28 indicates a flexible strand or

cable having its ends mounted, respectively, upon the end of the rack-bar and the lower end of the standard 17, said cable being in engagement with the pulleys 12, 14 and 24.

6 The pawl 29 is mounted upon a pin 30 carried by the frame, and is provided between its ends with a tread-plate 31. The pawl is normally in engagement with the teeth of the rack-bar by means of its spring 32, the 10 lower end of the spring being supported upon the chair 33 carried by the pin 26, the upper part of the chair being disposed upon the side-bars of the frame 21.

It will be seen that the operating parts for 15 moving the post 17 are disposed at a considerable distance, comparatively, from the wheels 8, this feature being of great advantage since the head of the swivel 18 may be disposed at the middle of a load having a 20 considerable area, and it will be noted that the horizontal frame, by the construction described, is disposed at all times closely adjacent to the floor, the operation of the pulley 24 maintaining the cable in the plane of the 25 frame, so that these parts will not be obtrusive.

In operation, if the hand lever is moved to 30 permit the pawl to engage the end of a tooth of the rack-bar, the pawl, by moving the tread-plate, may be disengaged from the rack-bar. An operator, by a rearward movement of the hand-lever, may then cause an 35 upward movement of the standard 17 for lifting a load, the pawl engaging and sliding on the teeth in a well known manner to the position shown in Fig. 1.

It will be appreciated that the use of a 40 cable, as shown effects a saving in the expense of manufacture and provides comparatively, a lighter structure, and since the cable is maintained in the plane of the horizontal side bars it is of particular advantage for communicating a movement to the vertical standard from the swinging movement 45 of the hand-lever.

What I claim as my invention and desire to secure by Letters Patent is,—

1. In a vehicle roller jack, an axle having 50 wheels journaled thereon, a casting projecting above and below and keyed on the axle and having a rectilinear channel opening on its upper end, a standard provided with a swivel and disposed in said channel, a rearwardly projecting horizontal frame keyed 55 on the axle and disposed at right angles to the channel, a pulley having journaled bearings on an upper part of the casting rearwardly of the channel, a pulley having journaled bearings on a lower part of the casting 60 rearwardly of the channel, and a cable engaging the pulleys and connected with the lower end of the standard and being mov-

able for moving the standard in line with said rectilinear channel.

2. In a vehicle roller jack, a casting having 65 rearwardly projecting, substantially parallel arms arranged in pairs, said casting being provided with wheels and having an upright channel midway between said wheels, a pair of rearwardly projecting side-bars each having its inner end disposed between said arms and a wheel and keyed on the casting, a standard in the channel, pulleys having journaled bearings in said rearwardly projecting arms, a flexible strand 70 connected with the standard and engaging the pulleys, and a hand-lever connected with the strand, said hand-lever having journaled bearings in and near the outer ends of the rearwardly projecting side-bars for moving 75 the flexible strand for elevating the standard.

3. In a vehicle roller jack, a casting provided with rearwardly projecting arms arranged in pairs, said casting being provided with wheels and formed with a rectilinear 80 channel, a standard in the channel, a pair of rearwardly projecting, convergent side bars each having its inner end disposed in a plane between a wheel and said rearwardly projecting arms and having a rigid connection 85 with said casting, pulleys having journaled bearings in said rearwardly projecting arms, and a movable strand engaging the standard and pulleys for moving said standard.

4. In a vehicle roller jack, a casting having 90 a channel and provided with wheels and also having a pair of upper, rearwardly projecting arms and a pair of lower, rearwardly projecting arms, a pulley having journaled bearings in the pair of upper arms, a pulley 95 having journaled bearings in the pair of lower arms, a standard in the channel of said casting, a frame consisting of a pair of rectilinear side-bars connected with and projecting rearwardly from the casting, a pair 100 of casters for said frame, means to maintain the frame at right angles to said channel, a cable engaging said pulleys and connected with the standard, a movable lever provided between its ends with a curved rack-bar and 105 connected with the opposite end of the cable, a chair spanning the side-bars of the frame, a pawl provided between its ends with a tread-plate, a spring on the chair for causing normal engagement of the pawl with the 110 curved rack-bar, and a third pulley engaging the cable for maintaining the cable in the plane of the frame.

In testimony whereof, I have affixed my signature in presence of two witnesses.

ARTHUR C. HOPKINS.
